UNITED STATES PATENT OFFICE

JOHN A. PRATT, OF NASHVILLE, TENNESSEE

TENSION DEVICE

Application filed March 27, 1929. Serial No. 350,368.

This invention relates to tension devices for knitting machines and has for its object the provision of a simple and efficient device which will effectually maintain the yarn under the proper tension and will prevent loss of the yarn or entanglement of the same while it is out of action.

In the accompanying drawings:

Figure 1 is a side elevation of a tension device embodying the invention,

Fig. 2 is a plan view of the same,

Fig. 3 is a detail front elevation, and

Fig. 4 is a rear elevation.

In carrying out the present invention, there is provided a frame or supporting bracket comprising a post 1, across the top of which is secured a plate 2 having eyes 3 therein at intervals to guide the yarn in an obvious manner. To the lower end of the post 1 is secured an offset transverse block 4 and to one end of this block is secured a foot 5 which is adapted to be secured to the frame of the knitting machine, a portion of which is shown at 6. Extended through and secured in the post 1 near the upper end thereof is a rod 7 having porcelain sleeves 8 mounted thereon at opposite sides of the post, and upon said sleeves are loosely mounted tension disks 9 which are arranged in pairs, as shown, and are adapted to press against the threads 10 passing through the several guide eyes 3 respectively alined therewith, it being understood that the eyes 3 are porcelain or similar bushings set in openings provided therefor in the cross plate 2, a smooth surface for free easy movement of the thread being thus provided and wear upon the metal parts being thereby reduced. The inner pairs of tension disks 9 are disposed adjacent the sides of the posts 1, as seen in Fig. 4, and between the inner disks and the outer disks expansion springs 11 are coiled around the sleeves 8 and bear against the several disks so as to yieldably hold the disks in engagement with the threads passing through the respective pairs. The innermost disks, as shown most clearly in Fig. 4, bear against the sides of the post and the mating disks are yieldably held thereto by the springs, while the outer disk of each outer pair bears against a thimble 12 which is fitted about the end por-

tion of the rod 6 and is held in a fixed position by a set nut 13 threaded onto the adjacent end of the rod.

The block 4 is constructed with a plurality of slits or notches 14 extending vertically across its rear side and within these respective notches are fitted angle levers 15, each of which has its upper arm disposed adjacent the post and the cross rod 7 with its upper extremity turned laterally, as shown at 16, and carrying a tapered spreader 17 which is adapted to enter between the related disks and separate the same. In order to obtain the proper coordination between the spreaders and the respective disks, the spreaders are constructed with longitudinal slots 18 and are held in a set position by screws 19 inserted through the respective slots into the upper ends of the levers. A lug or projection 20 upon the upper end of the lever limits the forward movement of the spreader and also cooperates with the holding screw to retain the spreader in right angular relation to the angle lever. The levers are pivotally held in the block 4 by a pin or pivot rod 21 inserted horizontally through the block and openings provided therefor in the respective angle levers and secured in place by a set screw 22 mounted through the top of the block, as shown in Figs. 1 and 4. The lower portion of each angle lever extends somewhat below the block 4 and terminates in a tapered tooth 23. Mounted upon the frame of the knitting machine in a block 24 are a plurality of intermediate levers or fingers 25 which are disposed in the vertical planes of the respective levers 15 and are each provided on its upper edge with a shoulder 26 adapted to abut the tooth 23 and rock the respective lever 15 so that it will carry its spreader 17 in between the adjacent tension disks and separate the same to release the yarn. These intermediate fingers or levers 25 extend to the front of the device, their front ends being turned downwardly, as at 27, to be engaged by the rear ends or heels of the controlling or thread-carrying fingers 28 which are mounted on the frame of the machine just over the needle circle and

are controlled by the pattern mechanism in the usual manner.

In knitting fancy hose, two yarns are knitted at the same time, one of the yarns being under constant tension and the other yarn being loose. The device of the present invention is for the purpose of holding the loose yarn when it is out of action. Each pattern thread 10 passes from the tension disks 9 to and through a guide eye 29 on the frame of the machine and thence to an eye in the end of the corresponding controlling finger 28, the taut thread 30 passing through an eye 31 in front of the eye 29 and thence to an eye in the same finger, as will be understood on reference to Fig. 1. The thread 30 runs through the usual tension device at the top of the machine (not shown) and is always under tension. The heel and toe thread 32 is also always under tension from a tension device (not shown) at the top of a machine and passes through an eye 33 to a finger 28 with which there is no cooperating intermediate finger.

In knitting fancy hose, there are always two threads. When the controlling finger is raised, the pattern threads carried thereby are out of action and the corresponding levers 25 and 15 assume positions which carry the spreader away from the tension disks and permit them to close on the thread 10 and hold it under the influence of the spring 11. The thread 10 is thus held firmly so that it may be cut cleanly and it will not miss the needles, one of which is indicated at 34, when it is again carried into action. When the controlling finger drops into action, the heel thereof rides against the pendent terminal 27 of the corresponding intermediate lever 25 and rocks the same so that the shoulder 26 thereon impinges upon the tooth 23 and rocks the corresponding lever 15, the spreader on said lever being thereby carried to and between the corresponding disks to separate the same and permit the thread to run loose.

Upon reference to Fig. 3, it will be noticed that there are five controlling fingers but only four levers. When the finger carrying the heel and toe thread or any one finger is down, the other four fingers are up.

Various changes in details may be made in adapting the invention to specific conditions without departing from the spirit or scope of the invention as the same is defined in the appended claims.

Having thus described the invention, I claim:

1. The combination of a support, pairs of tension disks thereon arranged to hold threads for a knitting machine, pattern-controlled fingers below the disks engaged with the respective threads, angle levers fulcrumed on the support below the tension disks, tapered spreaders carried by the upper ends of said levers to enter between and move from the

corresponding disks, intermediate fingers arranged below and engaging the lower ends of the levers for rocking the same, and pattern-controlled thread-carrying fingers below the intermediate fingers and in engagement therewith to selectively actuate the same. 70

2. The combination of a post, a cross bar thereon provided with guide eyes, pairs of thread-engaging disks supported at the side of the post below the cross bar and alined with respective eyes therein, a plurality of levers arranged in advance of and alined with the respective pairs of disks, spreaders carried by the upper ends of the levers to separate the coacting disks, the spreaders being adjustable across the ends of the respective levers, intermediate fingers below and extending across the lower ends of the respective levers and provided on their upper sides with shoulders to engage the lower ends of the levers, the free ends of said fingers being extended downwardly, and pattern-controlled thread-carrying fingers mounted below the intermediate fingers and having upturned ends bearing against the down-turned ends of the intermediate fingers to rock the same. 85

In testimony whereof I affix my signature.

JOHN A. PRATT. [L. s.]
